UNITED STATES PATENT OFFICE

2,520,628

LABEL PASTING MECHANISM WITH VARIABLE THROW LABEL PICKUP AND TRANSFER MEANS

Frank Elsner, Hanover, Pa.

Application May 25, 1949, Serial No. 95,247

5 Claims. (Cl. 216—55)

1

This invention relates generally to the class of label pasting and is directed particularly to improvements in apparatus for picking up a label and effecting the application of adhesive thereto and transferring the label to an object to which it is to be applied.

In the application of labels to objects of the nature of boxes and the like, particularly cigar boxes, it frequently occurs that the labels must be applied to boxes of different sizes so that mechanism for picking up a label from a stack, effecting the application of adhesive thereto and transferring the label to the box lid, or wall, must often be caused to change the extent of travel to suit the particular size of the object to which the label is being applied. It is accordingly a principal object of the present invention to provide an apparatus of this character wherein a novel means is provided for regulating the movement or throw of the label pick-up and transfer head.

Another object of the invention is to provide in a label pasting mechanism of the character stated, wherein a label pick-up suction head is swung from a pick-up position to a deposit position, novel mechanism which may be readily set or adjusted for the application of the label to a box lid or other object of maximum size or to one of a minimum size by restricting the extent of movement of the label carrying suction head over the surface upon which is located the object to which the label is to be applied.

Other objects and advantages of the invention will become apparent as the description of the same proceeds and the invention will be best understood from a consideration of the following detailed description taken in connection with the accompanying drawings forming a part of the specification, with the understanding, however, that the invention is not to be limited to the exact details of construction shown and described since obvious modifications will occur to a person skilled in the art.

In the drawings:

Figure 1 is a view in side elevation of mechanism constructed in accordance with the present invention showing one of two supporting standards between which the mechanism is carried and showing the movement control means set to permit the suction head to have its maximum swing for handling a label of maximum size.

Figure 2 is a view corresponding to Figure 1 but showing the control mechanism set to limit the throw or extent of movement of the label carrying suction head for handling a label of maximum size.

2

Figure 3 is a detail view on an enlarged scale showing the relative positions of the control mechanism and the suction head when the suction head is in the retracted position preparatory to picking up a label from a stack.

Figure 4 is a view in top plan of the machine, the tops of the standards being broken away and some of the lower structure beneath the hanger and control mechanism being omitted.

Referring now more particularly to the drawings the numeral 10 designates one of a pair of spaced standards between which is supported a rock shaft 11 carrying a hanger 12 which is designed to have swinging movement between two extreme positions at one of which positions is located a support of suitable character for a stack of sheets or labels 13 while at the other extreme position for the hanger there is located a table of suitable character upon which is placed a box lid or a complete box structure in proper position to have a label deposited thereon. Such supporting table 14 is here shown as having an inclined top surface 15 which is provided with a stop 16 at what may be termed the inner edge, that is, the edge nearest to the stack of sheets or labels.

The hanger 12 carries one or more longitudinal guides 17 through which is slidably extended a stem or pin 18 which carries at its lower end a label pick-up suction head which is generally designated 19 and which is of a standard character and which has associated with it a label gripping finger unit which is generally designated 20 and which, together with the head, is particularly disclosed and claimed in Patent No. 2,384,241 of September 4, 1945. The suction unit 19 is given slight reciprocal movement to facilitate the picking up of a label from the top of the stack 13 and depositing it upon an object lying upon the top surface 15 of the table 14 such, for example, as the member 21 which may represent the top of a box such, for example, as a cigar box, upon which a label is to be pasted.

For the operation of the suction unit 19 there is provided upon a suitable bearing 22, a rock arm 23, one end of which is connected by the link 24 with the pin or stem 18 while the other end has connected therewith a pitman 25 which is connected with a suitable source of power to effect the desired timed movement of the suction head in coordination with the swinging of the hanger 12 by which the head is supported.

Disposed between the stack of sheets or labels 13 and the table 14 are the paste or adhesive pick-up and transfer rollers 26 and 27 respectively. The transfer roller 27 is at such eleva-

tion that a label or sheet being carried by the pick-up head 19 from the stack to the body 21 on the table 14 will pass across and contact the surface of such roller so as to be supplied with the desired coating of adhesive.

Pivotedly mounted upon a suitable pivot stud or shaft 28 is a rock arm 29, the free end of which is directed forwardly in the general direction of the table 14.

Pivotedly connected at 30 with the free end of the arm 29 is a reciprocating pitman 31 by means of which power is transmitted to the arm and also to the hanger 12 through the mechanism about to be described.

Extending rearwardly from and rigidly joined to the pitman 31 is the pitman arm 32 and upon this arm at its rear end is pivotally connected by the pivot 33 a bell crank 34 which comprises a long arm 35 which extends forwardly and a short arm 36 which is directed upwardly.

The free end of the long arm 35 of the bell crank 34 is pivotally coupled with an end of a link 37, the opposite end of the link being pivotally connected at 38 to a short crank arm 39 which is rigidly connected with the upper end of the hanger 12.

The numeral 40 designates a sector plate which is pivotally mounted at its radial center upon the pivot 30. This sector plate lies across a side of the arm 29 with the arcuate edge portion thereof adjacent to the end of the arm which is mounted upon the pivot 28. This end of the arm carries a hub 28' across which the edge of the plate 40 extends and integral with this hub is an arcuate scale finger 41 which conforms to the edge contour of the adjacent portion of the plate 40, which portion has an arcuate slot 42 therein which is struck from the pivot 30 on which the plate swings. Between the slot 42 and the adjacent arcuate edge of the plate there is formed on the face of the plate a scale designating different box sizes or measurements, in accordance with which the swing of the hanger 12 is regulated, such scale being adjusted to a zero point 44 on the scale finger as shown in Figure 3.

For holding the plate 40 in adjusted position the arm 29 has threaded thereto a securing screw 45 which passes through the slot 42 and has its head in contact with the face of the plate.

Inwardly of the slot 42 is a longer and wider guide slot 46 in the plate 40, which is arcuate through a portion of its length from one end, concentric with the pivot 30. For the remainder of its length, to its other end, the slot is straight and tangent to the arcuate portion, as at 46'.

Slidably engaging in this slot 46 is a roller 47 which is carried upon the end of the short arm 36 of the bell crank 34. This arm 36 of the bell crank works between the plate 40 and the arm 29 as will be readily apparent.

In the operation of the present mechanism the swinging movement of the hanger for the suction head 19 is effected through the action of the pitman 31. As will be apparent, when the sector plate 40 is set as, for example, with the zero point 44 at the scale point 6½ to designate that the suction head 19 will have full swinging movement to take care of the maximum size box lid or body 21 as shown in Figure 3, when a down pull is applied to the pitman 31 the arm 29 and the plate 40 will be swung around the pivot 28 as a unit and the cam follower or roller 47 will move down in the slot 46 of the sector plate, a down pull being meanwhile applied to the link 37 to swing the hanger 12 forwardly.

The necessary actuation of the link 24 to lower the suction head to pick up a sheet from the stack 13 and reverse movement of the head has already been effected when this swinging action of the hanger 12 commences. When the pitman 31 and arm 29 reach the lowermost positions in their movement as shown in Figure 1, the suction head or unit 19 will be at the maximum forward position of its stroke but the follower 47 will be short

of the lower end of the portion 46' of the slot 46. If, however, the suction head is only to swing through part of its arc of movement as, for example, if a box lid 21 of maximum or 4 inch size is to have a label applied thereto, then when the parts are in the position shown in Figure 3, that is, when the suction head is at the limit of its back swing to label pick-up position, the locking screw 45 is loosened and the plate 40 is swung upwardly until the index 4 on the scale 43 comes to the zero point 44 whereupon the plate 40 is again fixed. When the pitman 31 then moves down on its power stroke to swing the hanger 12 the follower 47 will reach the lower end of the portion 46' of the cam slot 46 before the full swinging movement or full stroke of the hanger 12 with the suction head 19 is accomplished and such swinging movement will then be checked, stopping the suction head for the deposit of the label in the proper position upon the body 21 resting on the table.

In connection with this control mechanism it will be noted that the leading edge of the label in the stack has the same position for all sizes but may be deposited onto an article at any desired position within the maximum and minimum adjustments of the sector plate 40.

By reason of the form of the control slot in the sector plate 40, and adjustability of the sector plate, the swing arm or hanger 12, with the suction head 19, will move forward at a speed which is the same as the surface speed of the glue roll, for the maximum length of the label and thereafter the compensating portion 46' of the cam slot will effect reduction or restraint of the forward motion of the swing arm or hanger 12 to a desired depositing position.

With the mechanism herein disclosed it will be readily apparent that there is provided a simple, efficient and novel means for limiting or varying the throw or stroke of the label pick-up or suction head unit whereby, after the mechanism has been set for labeling a box lid or box top of a predetermined size, it may be operated continuously without further attention.

I claim:

1. In a label pasting mechanism, a label pick-up suction head, a swinging carrier for said head for shifting the head from a non-varying label pick-up position to a label deposit position, means for supporting a label in said pick-up position, means for supporting a body to receive a label at said deposit position, a reciprocable power transmitting element, and an adjustable linkage connection between said element and the swinging carrier for selectively changing the extent of movement of the carrier and head from said non-varying pick-up position to the deposit position.

2. In a label pasting mechanism, a label pick-up unit, means supporting the unit for back and forth movement between a non-varying label pick-up position and a label deposit position, means at the first named position for supporting a label, means at the second named position for supporting an article to receive the label, and an adjust-

able control means for selectively changing the extent of movement of the pick-up unit from the said non-varying position to the second named position.

3. In a label pasting mechanism, a swinging carrier, a label pick-up suction head carried by the carrier for movement from a label pick-up position to a label deposit position, means for supporting an object to receive a label at said deposit position, means for supporting a label at the pick-up position, a reciprocable power transmitting element, a pivoted arm having pivotal connection with said element, a crank carried by said element and having two arms, means connecting one of the crank arms with said swinging carrier, an element supported upon the pivot connection between the arm and the power transmitting element, means adjustably coupling the second named element with said arm, a sliding coupling between said second named element and the other arm of said crank element.

4. In a label pasting mechanism, a label pick-up suction head, a hanging carrier supported at one end for swinging movement and carrying the suction head upon the opposite and lower end, means for supporting an object to receive a label from the suction head at one position in the path of swinging movement of the head, means at the extreme position of swinging movement in the opposite direction for supporting a label for pick-up by the head, an arm pivotally supported at one end for swinging movement on an axis paralleling the axis of swinging for the carrier, a power transmitting member pivotally connected at one end to said arm, a sector plate

pivotedly attached on the pivotal connection between the arm and the power transmitting member, said sector plate having cam slot therein which is arcuate through a portion of its length from one end and straight through the remainder of its length to the other end, the arcuate portion of the slot being concentric with said pivotal connection, a bell crank pivotally supported upon the power transmitting member and having two angularly extending arms, a link connection between one of the bell crank arms and the swinging carrier, a sliding connection between the other one of the bell crank arms and said cam slot, and means for adjustably securing said sector plate adjacent to its radial edge to the first mentioned arm.

5. Label pasting mechanism of the character stated in claim 4, in which the said means for adjustably securing the sector plate to the first mentioned arm, comprises an arcuate slot in the sector plate concentric with the pivotal mounting for the plate and a securing screw extending through the said arcuate slot and engaging in the first mentioned arm.
